UNITED STATES PATENT OFFICE.

WILLIAM L. JENKINS, SR., OF CANONSBURG, PENNSYLVANIA, ASSIGNOR OF ONE-HALF TO JOHN A. HELLSTROM, OF WHEELING, WEST VIRGINIA.

APPARATUS FOR ANNEALING METAL PLATES AND SHEETS.

Application filed May 26, 1925. Serial No. 32,887.

My invention relates to apparatus for annealing metal sheets and plates.

One object of this invention is to provide an annealing furnace having a rotary carrier therein for the sheets or plates. Another object is to provide means outside the furnace for supporting at least the upper portion thereof. Another object is to build the furnace in sections from the level of the carrier, so that only a portion of the furnace walls will have to be taken out in order to remove the carrier. Other objects appear hereinafter.

Referring to the accompanying drawings, Fig. 1 is a top plan view of my annealing apparatus with a portion broken away; Fig. 2, a rear elevation of the said apparatus; Fig. 3, a central longitudinal view of the apparatus, portions being in side elevation; Fig. 4, a transverse section of the apparatus, the waste port 8' being shown on the opposite side of the furnace from its position in Fig. 1; Fig. 5, an end elevation thereof; and Fig. 6, a section of the upper part of the furnace, the section being on the upper half of the line 6—6 of Fig. 3.

On the drawings, 1 designates the foundation on which rests the furnace having the floor 2, the end walls 3 and 4, the front wall 5, the rear wall 6, and the removable roof 7 resting on the said end, front, and rear walls. The furnace has burner openings 8 in its side and end walls and near the lower portion thereof. 9 are the burners adapted to consume oil or gas. Other types of heating means may be employed. The waste gases escape from the furnace through the ports 8'.

I provide pillars 10 at the ends of the furnace. The pillars are spaced from the ends of the furnace and support the shaft 14 of the rotary carrier 12. The bearings are preferably of the roller type as shown at the left end of Fig. 3. The pillars as well as the driving machinery for the carrier and for the feeder to be described herein are supported on the metal bases 13 at the ends of the foundation 1. The shaft 14 lies in openings in the end walls of the furnace and is provided within the furnace with rows of metal fingers 15 running longitudinally of the shaft, the spaces between consecutive rows of fingers constituting pockets for the reception and transfer of the plates or sheets 16 to be annealed as the carrier rotates.

The shaft 14 has fixed thereon the spur-gear 17 which meshes with the pinion 18 on the shaft 19 supported by the bearings 20. The shaft 19 carries the worm-gear 21 which meshes with the worm 22 on the shaft 23 of the motor 27.

The shaft 19 has also the spur-gear 25 which meshes with the pinion 26 on the shaft 24 on which there is the crank 28 connected to the pitman 29. The pitman is pivoted to the arm 30 on the rock-shaft 31 mounted in the bearing 32. The front side of the furnace has at about the level of the shaft 14 a feeding slot 33 for the plates or sheets 16. 34 is a table at the front of the furnace with its horizontal top 35 in the plane of the lower lip of the opening 33. 36 is a pusher slideable on the table and having lugs 37 riding in the slots 38 in the top of the table. The rear edge of the pusher is pivoted on the rod 39 carried by the arms or links 40 fixed to the rock-shaft 31. Weights 41 are carried by the rear side of the rock-shaft. They tend to return the pusher to its extreme outer position.

The end of the shaft 14 opposite that which bears the gear 17 is provided with the gear 42 exactly like gear 17. It meshes with the pinion 43 which is exactly like the pinion 18, the latter being on the shaft 44 which carries the spur-gear 45. The latter meshes with the pinion 46 on the shaft 47 which carries the crank 48, connected by the pitman 49 to the arm 50 on the rock-shaft 31.

The rear of the furnace has below the level of the shaft 14 the outwardly and downwardly inclined discharge slot 51 arranged at an angle of about 45° between the horizontal and vertical planes which include the longitudinal axis of the shaft 14. There are a number of skids 52 which lie on the floor of the slot and extend into the furnace between the transverse rows of fingers 15, as shown in Fig. 1.

Near the corners of the furnace are the four pillars or standards 53 on which the I-beams 54 rest. These beams are connected together by the cross beams 55 resting on the pillars 10. The walls of the furnace are provided with a jacket of metal plates 56 having the flanges 57 supported by the beams 54 which carry a large portion of the weight of the furnace.

The end walls 3 and 4 have above the shaft 14 removable sections 58, as shown in

Fig. 6. These sections extend to the top of the end walls and are readily removable so that, when the roof has been lifted off, the shaft 14 may be easily lifted out of the furnace for repairs or replacement.

The shaft 14 is hollow and has the inlet and outlet pipes 59 for water circulation to keep the carrier cool. It will be noted the shaft 14 has lugs 60 extending out beyond its surface and serving as rests for the plates or sheets. These lugs allow the hot burning gases to flow in contact with all sides of the edges of the plates and sheets. The lugs cover only a very small length of the edge of a sheet or plate.

The operation is as follows: The motor 27 is started and causes the shaft 14 and carrier 12 to rotate, motion being transmitted through the worm 22, the worm gear 21, the shaft 19, and the gears 18 and 17. The shaft 19 rotates the gear 25 which drives the pinion 26. The latter rotates the crank 28 which operates the pitman 29, to rock the shaft 31 and cause the pusher 36 to reciprocate toward and away from the charging opening 33. Sheets are placed on the table 34 in front of the pusher each time the latter has moved to its back limit. At each forward movement of the pusher a sheet 16 is shoved into the furnace between two rows of fingers 15, the rotation of the carrier and the actuation of the pusher being timed to feed the sheets into consecutive spaces between the longitudinal rows of fingers. As the plates pass up over the shaft and down to their discharge position on the skids 52, they become suitably heated from the burners 9.

I claim—

1. In an apparatus for annealing metal sheets or plates, a furnace chamber, a rotatable shaft therein; radial fingers attached to the shaft and arranged in rows longitudinal

of the shaft, and forming spaces in which the sheets or plates are loosely held, projections at the bases of the fingers and above the periphery of the shaft to serve as seats for the inner edges of the sheets or plates whereby the inner edges of the sheets or plates are spaced from the shaft so that burning gases may pass between the shaft 45 and the said edges and between consecutive projections.

2. In an apparatus for annealing metal sheets or plates, a furnace chamber, a rotatable shaft therein, radial fingers attached to the shaft and arranged in rows longitudinal of the shaft, means whereby sheets may be fed into spaces between consecutive rows of fingers, a sheet or plate discharge passage through one side of the furnace, the passage 60 being below the level of the shaft, and downwardly and outwardly inclined skids arranged in the passage and projecting inwardly into the path of sheets or plates being conveyed downwardly by the rows of 65 fingers, whereby the sheets or plates will be discharged down the skids and prevented from accompanying their supporting fingers beyond the skids.

3. In an apparatus for annealing metal 70 sheets or plates, a furnace having a removable roof, and a rotary sheet or plate carrying shaft extending through the ends of the furnace and supported outside the furnace, the end walls of the furnace being built in 75 the said walls as a separate unit from the shaft to the top of the said walls, and the said unit being as wide as the diameter of the shaft where it passes through the walls, whereby the units may be removed without 80 disturbing other parts of the said walls.

In testimony whereof, I hereunto affix my signature this 23rd day of May, 1925.

WILLIAM L. JENKINS, SR.
